(57) **CLAIM**

The ornamental design for a lamp for road lighting, as shown and described.

DESCRIPTION

FIG. 1 is a bottom, front and left side perspective view of the lamp for road lighting showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a bottom plan view thereof; and,

FIG. 7 is a top plan view thereof.

The broken lines shown on the drawings represent environment only and form no part of the claimed design.
